Primary Examiner—Janice E. Seeger(74) *Attorney, Agent, or Firm*—Baker & Daniels(57) **CLAIM**

The ornamental design of a furniture end, as shown and described.

DESCRIPTION

FIG. 1 is a perspective view of a furniture end design, showing our new design;

FIG. 2 is an end view thereof;

FIG. 3 is front view thereof; and,

FIG. 4 is a sectional view taken along line 4—4 of FIG. 1 to illustrate the inset end panel.

The features which are shown in dashed lines form no part of the claimed design.
